Primary Examiner — Sandra Snapp*Assistant Examiner* — Bryan N. Melvin(74) *Attorney, Agent, or Firm* — Kirton McConkie; Brian Tucker(57) **CLAIM**

The ornamental design for a cable support, as shown and described.

DESCRIPTION

FIG. 1 is a top front perspective view of a cable support showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the cable support that form no part of the claimed design.
